DESIGN FOR A LANTERN SLIDE HOLDER

David L. Babcock and Theodore G. Clement,
Rochester, N. Y., assignors to Eastman Kodak
Company, Rochester, N. Y., a corporation of
New Jersey

Application April 8, 1941, Serial No. 100,227

Term of patent 14 years

To all whom it may concern:

Be it known that we, David L. Babcock and Theodore G. Clement, citizens of the United States, residing in Rochester, in the county of Monroe and State of New York, have invented a new, original, and ornamental Design for Lantern Slide Holder, of which the following is a specification, reference being had to the accompanying drawing, forming a part thereof.

In the drawing:

Fig. 1 is a front elevation of the lantern slide holder showing our new design;

Fig. 2 is a rear elevation of the lantern slide holder shown in Fig. 1;

Fig. 3 is a top plan view of the lantern slide holder shown in the preceding figures; and

Fig. 4 is an end elevation of the lantern slide holder shown in Figs. 1-3 inclusive.

We claim:

The ornamental design for a lantern slide holder, as shown.

DAVID L. BABCOCK.
